DESIGN FOR A FISH LURE

Clarence E. Greene and Dob Bradford,
Detroit, Mich.

Application February 24, 1947, Serial No. 137,144

Term of patent 7 years

(Cl. D31—4)

To all whom it may concern:

Be it known that we, Clarence E. Greene and Dob Bradford, citizens of the United States, residing at Detroit, county of Wayne, State of Michigan, have invented a new, original, and ornamental Design for a Fish Lure of which the following is a specification, reference being had therein to the accompanying drawings, forming a part thereof, in which

Fig. 1 is an end elevation of a fish lure, showing our new design.

Fig. 2 is a top plan view of the fish lure.

Fig. 3 is a side elevation of the fish lure.

Fig. 4 is a bottom plan view of the fish lure.

We claim:

The ornamental design for a fish lure, substantially as shown.

CLARENCE E. GREENE.
DOB BRADFORD.
